His ATTORNEY

UNITED STATES PATENT OFFICE.

FRANK H. NICHOLSON, OF PHILADELPHIA, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 28, 1924. Serial No. 734,714.

To all whom it may concern:

Be it known that I, FRANK H. NICHOLSON, a citizen of the United States, residing at Philadelphia, in the county of Philadelphia and State of Pennsylvania, have invented certain new and useful Improvements in Railway-Traffic-Controlling Apparatus, of which the following is a specification.

My invention relates to railway traffic controlling apparatus, and particularly to apparatus of the type comprising train carried governing apparatus controlled by energy received from the trackway.

I will describe one form of railway traffic controlling apparatus embodying my invention, and will then point out the novel features thereof in claims.

In the accompanying drawing, Fig. 1 is a diagrammatic view showing one form of trackway apparatus embodying my invention. Fig. 2 is a view, partly diagrammatic, and partly in cross section, showing one form of train carried apparatus arranged to co-operate with the trackway apparatus shown in Fig. 1 and also embodying my invention.

Similar reference characters refer to similar parts in both views.

Referring first to Fig. 1, the reference characters 1 and 1^a designate the track rails of a railroad over which traffic normally moves in the direction indicated by the arrow. These rails are divided, by means of insulated joints 4, into a plurality of successive track sections A—B, B—C, C—D, etc. Section B—C contains a permanent hazard such as a bridge, tunnel, curve, or some other hazard which requires that trains passing through this section shall not exceed some predetermined speed such as 30 miles per hour.

Each track section is provided with a track circuit comprising a suitable source of track circuit current, such as a track battery, connected across the rails adjacent the exit end of the section, and a track relay connected across the rails adjacent the entrance end of the section. Each such track battery is designated by the reference character E with a suitable exponent, and each track relay by the reference character R also with an appropriate exponent. The track relays may be used to control other traf-

fic controlling apparatus in any suitable manner.

Each section is also provided with a trackway signal designated by the reference character S with a suitable distinguishing exponent. As here shown, each signal S is a three position semaphore signal located adjacent the entrance end of the associated section but this particular form and location are not essential. Each signal is controlled in accordance with traffic conditions in advance in the usual manner, but since the circuits for such control form no part of my present invention they are omitted from the drawing for the sake of simplicity. For present purposes it is sufficient to state that each signal is so controlled that when the associated section is occupied the signal indicates stop; when the associated section is unoccupied and the section next in advance is occupied, the signal indicates caution; and when the corresponding section and the section next in advance are both unoccupied, the signal indicates proceed. Associated with each signal S is a circuit controller designated by the reference character F with an exponent corresponding to the location and arranged to be closed when the associated signal indicates proceed or caution but to be open when such signal indicates stop.

Means are also provided for at times supplying alternating train controlling current to the rails of sections A—B and C—D. For this purpose each of these sections is provided with a track transformer designated by the reference character T with a suitable exponent and having a secondary winding 3 interposed between the associated track battery E and one rail 1 of the corresponding section. The supply of energy to the primary of each such transformer is controlled by the circuit controller F for the section next in advance. Referring particularly to transformer T^b, when signal S^b is at proceed or caution the primary winding 2 of this transformer is supplied with alternating current over circuit controller F^b from terminals a and b of a suitable source of alternating current not shown in the drawing. It follows that section A—B is supplied with alternating train controlling current when signal S^b indicates proceed.

ceed or caution. The supply of train controlling current to section C—D is similarly controlled by signal S^p .

Spaced at intervals along the trackway in section B—C are train controlling devices or loop circuits W' , W^2 , each comprising two comparatively short conductors disposed parallel with the two track rails and connected in series. Alternating train controlling current is at times supplied to these devices from transformer T^c . The supply of energy to primary 2 of transformer T^c is controlled in the same manner as described for transformer T^b . It follows that each of the devices W is supplied with train controlling current when signal S^c indicates proceed or caution but not when signal S^c indicates stop. Under no condition is train controlling current supplied to the rails of section B—C.

The train carried apparatus comprises a pair of magnetizable cores 5 and 5^a located in advance of the forward axle 57 of the train illustrated diagrammatically at V in Fig. 1. The two cores 5 and 5^a are disposed above, and in inductive relation with, the two track rails 1 and 1^a , respectively. Carried on core 5 is a winding 6 and a similar winding 6^a is provided for core 5^a . These two windings are connected in series (see Fig. 2) so that the voltages induced in the windings by alternating train controlling current in the track rails or in the loops W are additive. These windings are constantly connected, preferably through a suitable amplifier 7 and a rectifier 8, with the magnet 9 of a magnet valve device M. It follows that when the train occupies a section of track the rails of which are being supplied with train controlling current, or when the cores 5 and 5^a are over an energized trackway device W , magnet 9 is energized.

The valve device M comprises a valve body 10 provided with an exhaust port 12 opening to atmosphere, an inlet port 14 constantly supplied with fluid under pressure from a source not shown in the drawing, and also with a pipe 22, the function of which will be explained hereinafter. When magnet 9 is de-energized, the double valve 11 is moved by a spring 13 into such position that pipe 22 is disconnected from port 14 and is connected with port 12, thus venting pipe 22 to atmosphere. When magnet 9 is energized, however, valve 11 is moved downwardly against the bias exerted by spring 13 and pipe 22 is then disconnected from atmosphere and connected with the source of fluid pressure by means of port 14.

A magnet repeater valve K is controlled by pipe 22 as follows: The valve K comprises a valve body 15 containing a cylinder which is divided into a right hand chamber 16 and a left hand chamber 17 by a piston 19. Chamber 17 is provided with a slide

valve 20 operated by piston 19. Pipe 22 is connected with chamber 16 and chamber 17 is constantly supplied with fluid pressure through pipe 14^a. Piston 19 is urged toward the left by a spring 21 so that when fluid pressure is supplied to chamber 16 by pipe 22, as when magnet 9 of valve device M is energized, the combined force exerted by this pressure and by spring 21 upon piston 19 forces the piston into its left hand or normal position against the pressure in chamber 17. When magnet 9 is de-energized, however, pipe 22 vents chamber 16 to atmosphere and the pressure in chamber 17 then over-balances the force exerted by spring 21 and piston 19 is moved to the right, or into its reversed position.

A restricted speed repeater valve J comprises a valve body 35 containing two chambers 37 and 38 separated by a piston 39 which is constantly urged to the left by a spring 58. Chamber 37 is constantly supplied with fluid pressure through pipe 14^b, and chamber 38 is connected with chamber 17 of valve K by means of pipe 33 when slide valve 20 of valve K is in the normal position.

When slide valve 20 of valve K is in the normal position, piston 39 of valve J occupies the left hand or normal position under the influence of the pressure in chamber 38 and the spring 58, thus moving slide valve 41 into the position illustrated in the drawing. When the pressure in pipe 33, and hence in chamber 38, is reduced, piston 39 and slide valve 41 operated thereby are moved into their right hand or reverse positions by the pressure exerted upon the left hand side of piston 39.

Associated with valve K is a release valve L biased to a right hand position by a spring 25. When valve K is normal fluid pressure is admitted to the right hand side of a flexible diaphragm 24 through pipe 14^c, recess 29^a in slide valve 20 and pipes 30 and 29. Pipe 29, communicating with the right hand side of diaphragm 24, is constantly connected with a blow-down reservoir 32. Under this condition, that is, when valve K is normal, the pressure on the right hand side of diaphragm 24 over-balances the bias of spring 25 and valve L is held in its left hand or closed position. When the pressure on the right hand side of diaphragm 24 is reduced below a predetermined value however, as will appear hereinafter, spring 25 moves valve L to the right and this valve then vents pipe 33^a to atmosphere through port 28.

A blow-down valve P and a low speed valve G are controlled by a speed governor H as will now be described. The governor H comprises a suitable housing 53 containing a shaft 51 which is actuated through suitable gearing 52 from an axle of the

train. Two weights 54 are arranged to be rotated by shaft 51 and, by virtue of the centrifugal force so generated, to move a crosshead 55 to the left against the bias exerted by a spring 56. It is plain that the greater the speed of the train, the farther crosshead 55 will be moved toward the left.

The low speed valve G is biased to a closed position by a spring 50. When the speed of the train exceeds some low value such for example as 15 miles per hour, crosshead 55 engages the end of stem 48 and opens the valve, thereby connecting chamber 49 with atmosphere. When valve J is reversed, chamber 49 of valve G is connected, by means of pipe 43 and slide valve 41, with a pipe 42 forming part of the automatic brake applying mechanism and arranged to apply the brakes when vented to atmosphere. When valve J is normal, pipe 43 is blanked by slide valve 41 and opening of valve G can not then apply the brakes.

Valve P comprises a chamber 51 having a piston 46 therein. The piston is biased by a spring 47 to a right hand position, in which pipe 34 is connected with the atmosphere through only a small orifice 45, and this is the position of the piston when the speed of the train does not exceed a given value. As the speed of the train increases above this given value, however, crosshead 55 of governor H engages the end of piston 46 and displaces this piston to the left against the bias of spring 47, the amount of this displacement being a function of the train speed. As piston 46 moves to the left the edge 46^a of the piston uncovers an auxiliary port 45^a for pipe 34 so that the greater the speed of the train the greater the area of the orifice through which pipe 34 can discharge to atmosphere. It should be pointed out that when valve K is reversed pipe 34 is connected, by recess 29^a in slide valve 20, with pipes 30 and 29 and blow-down reservoir 32.

As shown in Fig. 2 the train is proceeding at a speed greater than 15 miles per hour. Crosshead 55 is therefore moved to the left, opening valves G and P. Magnet 9 of valve device M is energized, so that valve K is in the normal position. As a result, blow-down reservoir 32 is charged from pipe 14^c and valve L is closed. The pipe 34 leading to the blow-down valve P is blanked by slide valve 20, and pipe 33 supplies chamber 38 of valve J with fluid pressure from pipe 14^a through chamber 17 of valve K. Valve J is therefore in the normal position. As a result slide valve 41 of this valve disconnects pipe 42 from pipe 43 and prevents pipe 42 from venting through valve G, now open. Under these conditions, the train is allowed to proceed at any speed without incurring a brake application.

I will now assume that the magnet 9 of

valve device M becomes de-energized, as by the entrance of the train into a section of track to which the supply of train controlling current has been interrupted. Valve device M reverses and vents chamber 16 of 70 valve K to atmosphere through port 12. Valve K therefore reverses. The reversal of valve K accomplishes three things, (1) pipe 30 is disconnected from pipe 14^c, (2) reservoir 32 and pipe 29 are connected, through 75 pipe 30, slide valve 20, and pipe 34, with the blow-down valve P, (3) and pipe 33 leading to chamber 38 of valve J is blanked by slide 20 and hence disconnected from its source of fluid pressure. The pressure in 80 reservoir 32 immediately commences to leak off through valve P. After a time interval the duration of which depends upon the amount of opening of valve P and hence upon the speed of the train, the pressure in 85 pipe 29 is so reduced that the force exerted on the right hand side of diaphragm 24 of valve L is less than the force exerted by spring 25 and the valve L opens, thus venting chamber 38 of valve J to atmosphere 90 through pipes 33 and 33^a, and port 28. Valve J then reverses to connect pipe 42 with valve G. The venting of pipe 42 through valve G, now open, applies the 95 brakes.

My invention thus provides apparatus on a train arranged when released to change from an initial condition to an ultimate condition in a time interval which decreases as the speed of the train increases, this apparatus being the blow-down reservoir which is normally in the initial condition of being charged with fluid pressure from pipe 14^c, the magnet repeater valve K, and the blow-down valve P, which valve P, when valve K is reversed, allows the pressure in reservoir 32 to dissipate to atmosphere till valve L opens, the time required for this reduction depending upon the train speed.

It should be pointed out that if, subsequent to the de-energization of magnet 9, and prior to the expiration of the time interval required to open valve L, the speed of the train is reduced to a value below 15 miles per hour, valve G will close and the reversal of valve J will not then apply the brakes. If, under these conditions the train again exceeds 15 miles per hour the brakes will immediately be applied by the opening of valve G, since valve J will, under these conditions, remain in the reversed position.

If, however, subsequent to the de-energization of magnet 9 and prior to the opening of valve L, magnet 9 is again energized, valve K is immediately moved to its normal position, recharging the reservoir 32 and disconnecting the reservoir from blow-down valve P. At the same time of course, pipe 33 is connected with chamber 17. As a result 125 the apparatus is restored to normal without 130

the operation of valves L and J, and the brakes are not applied. It should be pointed out that if magnet 9 is not re-energized until valves L and J have reversed, then 5 when magnet 9 is operated and valve K moves to the normal position, pipe 33 is connected to chamber 17 before valve L closes. To prevent large loss of fluid pressure before valve L closes a restricted passage 33^b is interposed in pipe 33 between chamber 17 and valve L.

Referring now also to Fig. 1, each time the train passes over one of the trackway devices W in section B—C, magnet M is energized. Assuming, as stated above, that it is desired to limit the speed of trains through this section to 30 miles per hour, the devices W are so disposed that the distance between each point where magnet M is de-energized 10 and the next successive point at which magnet M is energized is so great that a train proceeding at a speed in excess of 30 miles per hour will open its valve L and apply the brakes before the train traverses this distance. If, however, the train is proceeding at less than 30 miles per hour, the time interval required for the blow-down operation is great enough to bridge the time required to pass from one device W to the next 15 or the distance d in Fig. 1, and hence the brakes are not applied.

For example, I will assume that the time required after de-energization of magnet 9 before the brakes will be applied when the 20 train is traveling at 30 miles per hour is 27 seconds; at 25 miles per hour is 33 seconds; and at 40 miles per hour is 15 seconds. At 30 miles per hour the train will travel 1188 feet in 27 seconds. Consequently, the devices W are so disposed along the trackway that the distance d (Fig. 1) is 25 1188 feet. If the train proceeds into the section at 40 miles per hour it will travel only 880 feet before the brakes are applied. If, however, a train traverses the section at 25 miles per hour, the valve L will not open till the train has traversed 1210 feet. Obviously, the apparatus will be restored to its initial condition at the end of 1188 feet and the 30 train is therefore permitted to proceed through the section without a brake application.

If the train enters section B—C when signal S^c indicates stop, devices W are all de-energized, and valve 9, being de-energized throughout the block, will cause reservoir 32 to discharge in a time dependent upon the speed valve L to reverse at the predetermined pressure, and the brakes to apply if 35 the speed is above 15 miles per hour.

It should be understood that while I have, for purposes of explanation specified cer-

tain definite speeds, and certain definite time intervals for blow-down reservoir reduction, these values are not essential but would be 65 modified to suit local conditions.

Although I have herein shown and described only one form and arrangement of apparatus embodying my invention, it is understood that various changes and modifications may be made therein within the scope of the appended claims without departing from the spirit and scope of my invention.

Having thus described my invention, what 75 I claim is:

1. Railway traffic controlling apparatus comprising apparatus on a train arranged when released to change from an initial condition to an ultimate condition in a time interval which decreases as the speed of the train increases, means partially on the train and partially in the trackway for continually keeping said apparatus in its initial condition under safe traffic conditions but for releasing said apparatus under dangerous traffic conditions, brake applying mechanism set into operation when said apparatus reaches its ultimate condition, a portion of track containing a permanent hazard and 80 not equipped with trackway apparatus for keeping said apparatus continually in its initial condition, and devices in such portion of track for restoring said apparatus to its initial condition at intervals but so 85 arranged that if the speed of the train exceeds a safe maximum the apparatus will reach its ultimate condition.

2. Railway traffic controlling apparatus comprising a reservoir, means partially on 100 the train and partially in the trackway for connecting said reservoir with a source of fluid pressure under safe traffic conditions but effective under dangerous traffic conditions to disconnect the reservoir from said source 105 and connect the reservoir with atmosphere through an orifice the area of which increases as the speed of the train increases, brake applying mechanism on the train set into operation when the fluid pressure in 110 said reservoir is reduced below a predetermined value, a portion of track containing a permanent hazard and not equipped with trackway apparatus for continually keeping said reservoir charged to a pressure above 115 said predetermined value, and devices in such portion of track for charging said reservoir at intervals but so arranged that if the speed of the train exceeds a safe maximum the pressure in the reservoir will drop 120 below said predetermined value.

In testimony whereof I affix my signature.

FRANK H. NICHOLSON.
